Primary Examiner — Susan Bennett Hattan*Assistant Examiner* — Brett Miller(74) *Attorney, Agent, or Firm* — Jeffrey A. Proehl; Woods, Fuller, Shultz & Smith, P.C.(57) **CLAIM**

The ornamental design for a portion control device, as shown and described.

DESCRIPTION

FIG. 1 is a perspective view of the portion control device of the present disclosure;

FIG. 2 is a top plan view of the portion control device;

FIG. 3 is a bottom plan view of the portion control device;

FIG. 4 is a front elevational view of the portion control device;

FIG. 5 is a rear elevational view of the portion control device;

FIG. 6 is a left side elevational view of the portion control device; and,

FIG. 7 is a right side elevational view of the portion control device.
